UNITED STATES PATENT OFFICE.

JAMES EVERITT, OF LONDON, ENGLAND.

CLOTHES-HANGING APPARATUS FOR USE IN WARDROBES, TRUNKS, WAREHOUSES, AND THE LIKE.

1,263,216.

Specification of Letters Patent. Patented Apr. 16, 1918.

Application filed May 7, 1917. Serial No. 167,039.

To all whom it may concern:

Be it known that I, JAMES EVERITT, a subject of the King of Great Britain, residing at 11-19 Lever street, Goswell Road, London, E. C., in the county of Middlesex, England, have invented certain new and useful Improvements in Clothes-Hanging Apparatus for Use in Wardrobes, Trunks, Warehouses, and the like, of which the following is a specification.

The invention refers to the hanging of clothing from a tube in wardrobes, trunks and boxes, and provides the hereinafter described and claimed improvements relating thereto.

The invention provides such a tube by a plurality of pieces hinged together in a particular manner to form a single rigid length when opened out and when folded to reduce said length. The tube is adapted by a longitudinal slot for runners, from which garments are suspended, to work within its interior, and the particular manner of hinging the plurality of pieces for folding and for fastening them together when opened out to form a single rigid length forms the constructional features of the invention.

The improved construction is represented by the accompanying drawings.

Figure 1 shows a side elevation of a clothes-hanging tube formed of two pieces.

Fig. 2 is a side elevation, on a larger scale, showing the manner of hinging together the two pieces.

Fig. 3 is an underside plan of Fig. 2.

Fig. 4 is a side elevation similar to Fig. 2 but with the one tubular piece swung down or folded.

Fig. 5 is a cross section of Fig. 2 on the dotted lines.

The two pieces of the tube are represented at *a* and *c*, the latter being adapted to swing down and swing up on the piece *a*. The piece *a* at its one end is fixed to the supporting wall *y* of the wardrobe, trunk, or the like, or it may be otherwise so fixed.

The inner end of the piece *c* has its bottom portion entirely cut away for a distance, as at *c*⁴, making its section at this portion of deep inverted channel shape and of slightly larger size than the normal size of the tube, which enlarged size is provided by expanding the top *c*⁵ and sides *c*⁶ *c*⁷ of the tube at this end. Within the sides *c*⁶ *c*⁷

are provided opposite similarly-shaped slots *m* and *n*, extending longitudinally, and also vertically at the inner extremities of said slots, to make said slots bayonet-slot like. This enlarged end of the extension piece *c* is adapted to fit over the normal sized and sectioned end *a*⁴ of the fixed tubular piece *a*, said enlarged end transversely clipping the normal sized end to efficiently stay the two tubular pieces *a* and *c* to each other both sidewise and longitudinally. Opposite pivot pins *t* and *u* rigidly project from the sides of the piece *a* to engage the slots *m* and *n*, which engagements form permanent connecting devices between the two tubular pieces *a* and *c*. When the tubular piece *c* hangs down in its folded position, as in Fig. 4, the pins *t* and *u* engage the outer ends *v* of the slots. When said piece forms a rigid length, as in Figs. 1, 2, 3, and 5, said pins *t* and *u* engage the right angled portions *v*² of said slots, in which portions the extreme end *c*² of the top *c*⁵ engages beneath a projection *w* fixed to the tubular piece *a*.

When the two pieces *a* and *c* form a rigid tube length, as in Figs. 1, 2, 3 and 5, disengagement of the piece *c* from the projection *w* is prevented by the engagement of the pins *t* and *u* with the portions *v*² of the slots *m* and *n*, requiring an initial lifting of the tubular piece *c*, to clear the pins *t* *u* of the portions *v*², before the joint can be broken and the piece *c* swung down.

The cross section of the tubular pieces *a* and *c* except at the inner end of the piece *c*, where its bottom portion is entirely cut away for a distance, is such as to provide the two tubular pieces *a* and *c* with a continuous longitudinal slot, *x*, in its bottom portion to accommodate the depending parts of runners or trolleys, such as *s*, indicated by dotted lines in Figs. 2 and 5, the wheels *s*², *s*³, of such runners rolling on the bottom portions, *x*², *x*³, of the two pieces.

When the two pieces *a* and *c* are rigidly fixed to each other to form a one-length tube the runners or trolleys *s* can travel the interior of the length of said pieces and the garments suspended from them may be easily separated for sorting, etc., while when the piece *c* swings down, as in Fig. 4, all the runners have been previously moved onto the piece *a*.

Having now described my invention what

I claim and desire to secure by Letters Patent is:—

1. A tube for the purpose specified, comprising a plurality of pieces provided with slots for suspending runners or trolleys to work within them and one piece of which is fixed, and means for hinging the plurality of pieces to each other so that said pieces may form a single rigid length with the slots for the runners or trolleys always in line, the movable piece being downwardly movable on the fixed piece, substantially as described.
2. A tube for the purpose specified, comprising a fixed piece longitudinally slotted at its bottom portion and carrying a fixed projection and opposite hinging pins, a hinged piece enlarged at its inner end to

longitudinally and transversely clip the adjacent end of the fixed piece and whose bottom portion is also longitudinally slotted and which piece is provided with side slots to engage the hinge pins and arranged so that it engages the projection on the fixed piece, and suspender runners or trolleys adapted to work within the two pieces and to project through the longitudinal slots in their bottom portions, substantially as described.

In testimony whereof I have hereunto set my hand in presence of two subscribing witnesses.

JAMES EVERITT.
